(57) **CLAIM**

The ornamental design for a pneumatic tire, as shown and described.

DESCRIPTION

FIG. 1 is a perspective view of a pneumatic tire of my new design, it being understood that the pattern repeats uniformly throughout the circumference of the tire;

FIG. 2 is a front elevational view of a pneumatic tire of my new design, it being understood that the pattern repeats uniformly throughout the circumference of the tire;

FIG. 3 is a side elevational view of a pneumatic tire of my new design, it being understood that the pattern repeats uniformly throughout the circumference of the tire;

FIG. 4 is a side elevational view of a pneumatic tire of my new design, taken from the opposite side shown in FIG. 3, it being understood that the pattern repeats uniformly throughout the circumference of the tire; and,

FIG. 5 is an enlarged, partial view of the pneumatic tire of FIG. 1, it being understood that the pattern repeats uniformly throughout the circumference of the tire.

In the drawings, the broken lines defining the inner bead depict environmental subject matter that forms no part of the claimed design. The dash-dot lines represent the boundary between the claimed tire tread and sidewall and the unclaimed inner bead. The sidewall is understood to repeat uniformly throughout the circumference of the tire; and the tread pattern is understood to repeat uniformly throughout the circumference of the tire.
